UNITED STATES PATENT OFFICE

DAVID E. CARLSON, OF MINNEAPOLIS, MINNESOTA

DESIGN FOR A WEDDING RING

Application filed February 16, 1931. Serial No. 38,685. Term of patent 3½ years.

To all whom it may concern:

Be it known that I, DAVID E. CARLSON, a citizen of the United States, residing at Minneapolis, in the county of Hennepin and State of Minnesota, have invented a new, original, and ornamental Design for a Wedding Ring, of which the following is a specification, reference being had to the accompanying drawing, forming part thereof.

The figure is a perspective view of the wedding ring, showing my new design, the opposite side of which is identical with that shown in the drawing.

I claim:

The ornamental design for a wedding ring, substantially as shown and described.

DAVID E. CARLSON.
